UNITED STATES PATENT OFFICE

2,322,816

GALVANOMETER

Harold T. Boeker, Chicago, Ill., assignor to General Electric X-Ray Corporation, Chicago, Ill., a corporation of New York

Application May 25, 1940, Serial No. 337,177

7 Claims. (Cl. 171—95)

My invention relates in general to electrical measurement, the invention pertaining more particularly to electro-magnetic galvanometer construction.

An important object of the present invention is to provide an electro-magnetic galvanometer in which the action of the instrument is substantially unaffected by changes in frequency throughout a wide frequency range of the electrical phenomena to which the instrument is subjected.

Another important object is to provide an electro-magnetic galvanometer adapted for the accurate indication of heart sounds and electrocardiac phenomena, for which purpose the galvanometer necessarily is characterized by a flat frequency response for all frequencies up to frequencies of the order of 1,000 cycles per second in order to indicate all of the harmonics contained in the heart action under observation.

Another important object is to provide an instrument of the character mentioned of sufficiently rugged construction to withstand the vibration and shocks to which portable indicating and recording apparatus is necessarily exposed in service.

Another important object is to provide an indicating device having a movable mirror mounting in which frictional resistance to movement is a minimum; a further object being to mount the mirror at one end of a thin spring steel ribbon, the other end of which is fastened to the armature of the galvanometer, and to confine the ribbon between opposed coaxial needle supports, whereby to obtain substantially undamped movement of the mirror proportional to armature movement.

Among the other numerous important objects, advantages, and inherent functions of the invention is to provide a highly sensitive galvanometer of rugged character, yet extremely simple of adjustment and operation; to provide a galvanometer in which the mechanical parts are substantially free of the damping effects of friction; to provide a galvanometer having a substantially flat frequency response; and, in general, to provide a galvanometer suitable for use in accurately recording electrical phenomena fluctuating within the audio frequency range, as, for example, the recordation of voice or music on sound track of motion picture film and the recordation of heart sounds or cardiac voltages.

These and numerous other important objects, advantages, and inherent functions of the invention will be fully understood from the following

description, which, taken in connection with the accompanying drawing, discloses a preferred embodiment of the invention.

Referring to the drawing:

Figure 1 is a graphical representation of galvanometer frequency response;

Figure 2 is an enlarged sectional view through a galvanometer embodying my present invention;

Figure 3 is an enlarged somewhat diagrammatic representation of the armature and mirror mount forming a part of the galvanometer shown in Figure 2; and

Figure 4 is a sectional view taken substantially along the line 4—4 in Figure 2.

To illustrate my invention, I have shown on the drawing a galvanometer 11, comprising an actuating coil 13 mounted in operative position with respect to a core 15, an armature 17, and a movable mirror mounting 19 connected to the armature.

The core forms a magnetic circuit and comprises preferably a permanent magnet 21 provided with preferably silicon steel pole pieces 23 mounted on the poles of the magnet 21 in opposing relationship, the pole pieces being notched or cut out, as at 25, to provide a space in which the coil 13 is mounted, said pole pieces each comprising arms 27 and 28 on opposite sides of the notches 25, the corresponding arms of the pole pieces being disposed in facing spaced apart relationship to provide spaces between the pole pieces at the opposite ends of the coil 13 in which spaces the armature 17 is mounted.

The armature 17 preferably comprises a silicon steel stem having an end 38 anchored in an armature support 29, which is fastened in any suitable fashion rigidly with respect to the core 15. The armature 17 comprises preferably a

flat strip of material and extends from its mounting in the air gap between the facing arms 27 of the pole piece on one side of the coil, thence through the coil, which is wound preferably on a suitable spool 31 to give the armature ample clearance for movement within the coil. The end 35 of the armature 17 remote from the mounting 29 extends in the space between the facing ends of the arms 28 of the pole pieces.

When the coil 13 is energized, the end 35 of the armature 17 will be caused to move under the combined influences of the magnet 21 and the magnetic effect produced by the energized coil 13. The movement of the armature, transferred to the movably mounted mirror 19, will cause the same to move in exact accordance with

the movement of the armature, providing there is no frictional retardation or damping or lost motion in the connection between the armature and the mirror. Mirror movement, though slight, may be amplified by arranging the mirror to reflect light from a fixed source 37 onto a recording surface 39 of any convenient character such, for example, as a light-sensitive film.

In order to eliminate lost motion and the effects of mechanical friction from the armature-mirror connection, the mechanism 19 comprises a ribbon 41 of suitable material, such as steel or phosphor bronze, to one end of which a mirror 43 is attached, the other end of the ribbon 41 being fastened, as by means of silver solder or spot welding, to the end 35 of the armature 17. The ribbon 41 is fixed on the armature preferably in alignment therewith and extends between a pair of coaxial restraining needles 45, the points of which engage the opposite sides of the ribbon 41 substantially on the medial axis thereof.

The needles 45 are preferably supported in embossments 47 formed on the arms 28 of the pole pieces 23, the needles preferably being threaded in said embossments, whereby the same may be axially adjusted therein and fastened in adjusted position as by the clamp nuts 49.

The coil 13 comprises a suitable number of turns of preferably copper wire wound upon the spool 31 which is fastened in place upon the pole pieces 23 in any suitable or convenient fashion. Suitable leads 50 are, of course, provided for connecting the coil with the external circuits in which exist the electrical phenomena to be indicated or recorded. I provide for electrically dampening the galvanometer by applying means forming a closed circuit around the coil. Said circuit forming means may take the form of an annular band 51 of suitable conducting material, such as copper, applied at the periphery of the coil 13, or may comprise several turns of conductor wire applied to the coil.

In order to provide for adjusting the damping effect of the circuit forming means 51, the circuit may include an adjustable resistor 53 inserted in series in the damping circuit, as by interrupting the band 51, as at 55, and connecting the adjustable resistor 53 in the circuit at said interruption, as clearly shown in Figure 4 of the drawing.

When current flows through the coil 13 in the direction indicated by the arrows in Figure 2, a north pole is established at the end 35 of the armature, and a flux is set up in each of the magnetic circuits defined by the armature 17, the air gaps 12, 14, 16 and 18, and the pole pieces 23. The condition thus established causes the end 35 of the armature, constituted as a north pole, to move toward the south pole of the permanent magnet 21, which will be toward the left, viewing Figure 2, in which the left-hand arm of the magnet 21 is designated as a south pole. This movement is due to the fact that the flux established in the armature divides, as shown, with part Df_2 of the total armature flux flowing through the air gap 14 and the south pole piece 23 of the permanent magnet, thence back to the armature through the air gap 18, while the balance Df_3 of the flux flows through the air gap 12 and the north pole piece 23 of the magnet and thence back to the armature through the air gap 16. At the upper end of the armature 35, the flux Df_2 in the air gap 14 is cumulative with respect to the flux f_1 , the steady flux through the air gaps caused by the action of the permanent magnet, 75

while in the air gap 12, the flux Df_3 opposes or is differential with respect to the steady flux f_1 . The force tending to pull the armature toward the south pole is therefore greater than that tending to pull the armature toward the north pole. These forces may be expressed mathematically as follows:

The resultant flux in the air gap 12 is $f_1 - Df_3$ and in the air gap 14 is $f_1 + Df_2$.

The force tending to pull the armature toward the north pole is

$$F_1 = K_1(f_1 - Df_3)^2$$

while the force tending to pull the armature toward the south pole is

$$F_2 = K_1(f_1 + Df_2)^2$$

The resultant force on the armature is therefore

$$F = F_2 - F_1 = K_1(2.f_1.Df_2 + 2.f_1.Df_3 + Df_2^2 - Df_3^2)$$

When the deflection of the armature from central position is small Df_2 will be substantially equal to Df_3 , the difference being of infinitesimal character, so that by substituting Df_3 for Df_2 in the foregoing equation

$$F = 4.K_1.f_1.Df_2$$

If the armature is not saturated, the total flux therein will be directly proportional to the current flowing in the coil 13 so that

$$Df_2 = K_2.I_m.\sin \text{wt.}$$

By substituting the foregoing value for Df_2 in the preceding equation

$$F = K_3.I_m.\sin \text{wt.}, \text{ where } K_3 = 4.K_1.K_2.f_1$$

because f_1 is constant.

For very small deflections of the armature, the elastic limit of the steel is not exceeded, and therefore the deflection of the armature is proportional to the force or

$$D = K_4.I_m.\sin \text{wt.}, \text{ in which } I_m. \sin \text{wt.}$$

is current in the coil.

The foregoing equation indicates that the deflection is proportional to the current in the coil, providing the galvanometer is designed in accordance with the stated conditions. Consequently, a light beam emanating from the source 37 will be deflected by the mirror 43 upon the surface 39 by an amount exactly proportional to the current flowing in the coil 13 so long as the deflection of the armature is slight and the elastic limit of the steel is not exceeded.

When a force is exerted upon the armature due to the flow of current in the coil 13, the armature will be deflected, as indicated in Figure 3 of the drawing, to a position shown in dotted lines. If T_2 be the angle between the original and deflected positions, then for very small deflections of the armature, the following geometric relations are substantially true:

$$T_1.b = T_2.a; \text{ or } T_1 = T_2.a/b$$

where a equals the length of the armature 17 and b equals the distance along the ribbon 41 from the end of the armature to the restraining pins 45.

Since the mirror 43 is mounted rigidly on the end of the ribbon 41, it will be deflected through an angle T_1 , and from the foregoing equation, it can be seen that by making b relatively small compared with a , a large multiplying factor for the sensitivity of the instrument can be obtained.

The foregoing geometric relation holds true

for small deflections of the armature where movement of the armature does not cause any appreciable bending of the ribbon 41.

Instruments embodying my present invention have a substantially flat frequency response for all frequencies up to the order of 1000 cycles per second, as shown in the curve B in Figure 1, in which curve A represents the typical response of coil type instruments of the character heretofore available. It will be noted that curve B includes a peak portion C, which represents a phenomenon caused by the action of the springs at resonance. The resonant effect, however, occurs at the upper limit of the frequency range of the instrument and will not affect the operation of the same within its normal working limits.

It is thought that the invention and numerous of its attendant advantages will be understood from the foregoing description, and it is obvious that numerous changes may be made in the form, construction and arrangement of the several parts without departing from the spirit or scope of the invention, or sacrificing any of its attendant advantages, the form herein described being a preferred embodiment for the purpose of illustrating the invention.

The invention is hereby claimed as follows:

1. In an instrument of the character described, including an armature movable in response to electrical impulses, the combination with said armature of means forming a flexible extension on said armature, a mirror on said extension, and means confining said extension for rocking movement about an axis extending substantially midway between the armature and the mirror.

2. In an instrument of the character described, including an armature movable in response to electrical impulses, the combination, with said armature, of means forming a flexible extension on said armature, a mirror on said extension, and means comprising opposing abutments on opposite sides of said extension for confining said extension for rocking movement about an axis located between the armature and the mirror and spaced from said mirror.

3. In an instrument of the character described, including an armature having an end movable in response to electrical impulses, the combination with said armature of a mirror, a resilient ribbon of self-supporting material having an end rigidly fastened to the movable end of said armature, said mirror being rigidly fastened to

the other end of said ribbon, and confining means comprising coaxial aligned pins in position engaging the opposite sides of said ribbon intermediate the ends thereof.

5. In an instrument of the character described, including an armature having an end movable in response to electrical impulses, the combination with said armature of a mirror, a resilient ribbon of self-supporting material having an end rigidly fastened to the movable end of said armature, said mirror being rigidly fastened to the other end of said ribbon, and confining means comprising coaxial aligned pins in position engaging the opposite sides of said ribbon intermediate the ends thereof, said pins being adjustable in the direction of their aligned axes.

10. In an instrument of the character described, an armature movable in response to electrical impulses, said armature comprising a member rigidly anchored at one end whereby armature movement is confined by the elasticity of the armature material, means forming a flexible extension on said armature, a mirror on said extension, and means forming abutments on opposite sides of said extension for confining said extension for rocking movement about an axis disposed between the armature and the mirror.

15. In an instrument of the character described, an armature movable in response to electrical impulses, said armature comprising a member rigidly anchored at one end whereby armature movement is confined by the elasticity of the armature material, means forming a flexible extension on said armature, a mirror on said extension, and co-axial pins aligned in position engaging opposite sides of said flexible extension for confining the movement thereof between the armature and the mirror.

20. In an instrument of the character described, an armature movable in response to electrical impulses, said armature comprising a member rigidly anchored at one end whereby armature movement is confined by the elasticity of the armature material, means forming a flexible extension on said armature, a mirror on said extension, and co-axial pins aligned in position engaging opposite sides of said flexible extension for confining the movement thereof between the armature and the mirror.

25. In an instrument of the character described, an armature movable in response to electrical impulses, said armature comprising a member rigidly anchored at one end whereby armature movement is confined by the elasticity of the armature material, means forming a flexible extension on said armature, a mirror on said extension, and co-axial pins aligned in position engaging opposite sides of said flexible extension for confining the movement thereof between the armature and the mirror.

30. In an instrument of the character described, an armature movable in response to electrical impulses, said armature comprising a member rigidly anchored at one end whereby armature movement is confined by the elasticity of the armature material, means forming a flexible extension on said armature, a mirror on said extension, and co-axial pins aligned in position engaging opposite sides of said flexible extension for confining the movement thereof between the armature and the mirror.

35. In an instrument of the character described, an armature movable in response to electrical impulses, said armature comprising a member rigidly anchored at one end whereby armature movement is confined by the elasticity of the armature material, means forming a flexible extension on said armature, a mirror on said extension, and co-axial pins aligned in position engaging opposite sides of said flexible extension for confining the movement thereof between the armature and the mirror.

40. In an instrument of the character described, an armature movable in response to electrical impulses, said armature comprising a member rigidly anchored at one end whereby armature movement is confined by the elasticity of the armature material, a resilient ribbon of flexible self-supporting material having an end rigidly fastened to said armature to form a flexible extension on said armature, a mirror on said extension, and means confining said extension for tilting movement about an axis therein and spaced from said mirror.

HAROLD T. BOEKER.
